WITNESS:

UNITED STATES PATENT OFFICE.

CHARLES EDWARD JONES, OF NEW YORK, N. Y.

TELEPHONE ATTACHMENT.

1,388,720.

Specification of Letters Patent. Patented Aug. 23, 1921.

Application filed May 17, 1920. Serial No. 382,093.

To all whom it may concern:

Be it known that I, CHARLES EDWARD JONES, a citizen of the United States, residing at New York city, in the county of New 5 York and State of New York, have invented new and useful Improvements in Telephone Attachments, of which the following is a specification.

This invention relates to telephones, particularly to attachments therefor, and has 10 for its object the provision of a device interposed between the transmitter and mouth piece and embodying a shutter which is operable to cover or uncover the opening in the mouth piece and which is for the purpose 15 of excluding from the transmitter objectionable noises such as are present in factories, work-shops, and other places, it being well known that these noises are transmitted to the party at the other end of the 20 line and cause confusion and annoyance.

An important object is the provision of a 25 device of this character which may be attached to a telephone without making any alterations therein and which is so constructed that it is normally spring-pressed into such position as to permit the passage 30 of sound into the transmitter while capable of being very quickly adjusted to shut off sound.

An additional object is the provision of a 35 device of this character which will be simple and inexpensive in manufacture, highly efficient in use, durable in service, and a general improvement in the art.

With the above and other objects and advantages in view, the invention consists in the details of construction to be hereinafter more fully described and claimed, and illustrated in the accompanying drawings in 40 which—

Figure 1 is a side elevation of a telephone equipped with my device,

Fig. 2 is a longitudinal sectional view 45 through my device, and

Fig. 3 is a cross sectional view.

Referring more particularly to the drawings, the letter A designates the transmitter of a telephone, and B designates the 50 mouth piece thereof. My device is adapted for interposition between the transmitter and mouth piece and comprises a cylindrical casing 10 constructed of any desired size and of any suitable material, and of 55 any number of parts necessary, though in the drawings I have shown it as formed in

two sections 11 and 12. The section 11 is provided centrally with a tubular extension 13 externally threaded for engagement with in the threaded opening in the transmitter. 60 The section 11 is provided centrally with a tubular extension 13 externally threaded for engagement within the threaded opening in the transmitter. The section 12 is formed centrally with an internally threaded extension 14 within which the mouth piece B is screwed. In this way my device is firmly associated with the telephone.

Located within the casing 10 is a segmental shaped shutter 15 pivoted at 16 and provided with an elongated extension 17 movable through a slot 18 in one side of the casing and provided at its end with a pendant chain 19 serving as a handle. The shutter is formed with a rounded hole 20 adapted 70 to register with the opening leading into the transmitter and the shutter is engaged by a leaf-spring 21 which normally holds it in such position that the hole 20 registers with the opening in the transmitter and 75 permits the passage of sound. When it is desired to cut off the sound entering the transmitter, as for instance when one is listening to or receiving a message in a noisy place, it is merely necessary that the operator pull downwardly upon the chain 19 which will move the shutter so as to cover the opening in the transmitter. It will thus be seen that objectionable noises will not be heard by the other party telephoning. 80

From the foregoing description and a study of the drawings it will be apparent that I have thus provided a simply constructed and efficient device which is easy to install and which will render a transmitter sound-proof and consequently not only prevent undesired noises or remarks being heard by the party at the other end of the line but will also make the message received clear as doing away with interfering vibrations.

While I have shown and described the preferred embodiment of my invention, it is of course to be understood that I reserve the right to make such changes in the form, construction, and arrangement of parts as will not depart from the spirit of the invention or the scope of the subjoined claim.

Having thus described my invention, I claim:

A telephone attachment comprising a casing formed of detachably connected sec-

tions, one section being formed with an outwardly extending central flange externally threaded for engagement within the threaded hole of a telephone transmitter and the 5 other section being formed with a central internally threaded hole for engagement therein of the threaded end of the telephone mouth piece, a shutter pivoted within said casing and including a relatively large 10 plate-like head portion and a relatively long and narrow extension constituting a handle, the side of the casing being formed with a

slot through which said handle extension extends, said shutter being formed at one end of the head portion with a hole adapted to 15 register with the hole encircled by said flange, and a leaf spring secured within the casing and engaging said head portion for normally holding the shutter with the hole therein registering with the hole in the 20 transmitter.

In testimony whereof I affix my signature.

CHARLES EDWARD JONES.
